Inventor:

Willy Freund

UNITED STATES PATENT OFFICE.

WILLY FREUND, OF CHEMNITZ, GERMANY.

SPINNING MACHINE.

Application filed March 6, 1925. Serial No. 13,546.

To all whom it may concern:

Be it known that I, WILLY FREUND, a citizen of the German Republic, residing at Chemnitz, Saxony, Germany, have invented 5 certain new and useful Improvements in Spinning Machines, of which the following is a specification.

This invention relates to a spinning apparatus of the kind in which the spindle is 10 fitted with a slideable cap between which and a support for said cap the yarn is led, and the invention consists essentially in the provision of a cap support in the form of a plurality of balls or rollers arranged rotat- 15 ably in a stationary cage so that the yarn is subjected to a succession of instantaneous retardations. The supporting elements are arranged detachably in the cage so that their number can be varied according to the 20 required retardation effect. The cap bears against the supports by means of a detachable rim which can be exchanged to suit the nature of the material.

The invention also includes various other 25 features in connection with the cap and with the support, as will be hereinafter described.

Fig. 1 of the accompanying drawings represents a side view of the cap and its sup- 30 port, partly in section, and

Fig. 2, a cross-section of the same on a larger scale taken on the line 2—2 of Fig. 1.

Fig. 3 is a partial plan of a ball cage according to one construction, and

Fig. 3^a, a partial plan of another con- 35 struction.

Fig. 4 is a plan of a roller cage.

Fig. 5 is a sectional side view on a larger 40 scale showing one construction of the ball cage.

Fig. 6 is a side view showing the ball cage support in section, and

Fig. 7 is a plan of the ball cage support.

Fig. 8 is a sectional view showing a re- 45 silient connection between cap and spindle, and

Fig. 9, a plan of the same.

Figs. 10, 11, 12 and 13 are sectional views 50 showing ball cages of different constructions with resiliently supported rollers.

Fig. 14 is a plan of the arrangement shown in Fig. 12.

Slidably connected to the spindle 7 is a 55 cap 3 having at its lower edge a detachable rim 11 whereby it rests on a support formed by one or more balls or rollers which are

held in and controlled by a cage 12. The yarn is led in between the cap and the support and will be subjected, during each revolution of the spindle, to a succession of 60 instantaneous retardations as it moves with the cap over the supporting points. The balls or rollers are arranged so that they can be easily removed and refitted for the purpose of varying their number according 65 to the nature of the yarn and to the desired retardation effect. There may be only a single row of balls, as shown in Fig. 3, or, if the rim 11 is wide, two rows, as shown in Fig. 3^a, the balls of different rows being 70 in the latter instance arranged in a staggered position so as to come into play alternately. By this arrangement the retardation of the yarn can be regulated within a very wide range.

Fig. 5 shows the preferred construction of the ball cage. A flanged ring 15, having apertures in which to hold the balls 13, is screwed on to a ball supporting rim 16. A space 17 is formed between the two rings so 75 that the dust can be readily discharged through the ring 16 from between the balls 13.

A similar arrangement may be used to take rollers 14 or the like (Fig. 4) instead 80 of balls.

The cage may be connected to the ring rail 18 either direct as shown in Fig. 1, or through the medium of a ring 20 which is split at 19 (Figs. 6 and 7) so that it can 90 be clamped to the cage. A screw 21, which is fitted in the rail 18, clamps the ring 20 to the cage as well as to the rail.

In the arrangement shown in Fig. 1, the cap 3 is formed with a neck 2 into which is 95 screwed a bushing 4. The latter is formed with conical orifices 5 and with a flat central channel 6 for engagement with the flat faces 8 of the spindle. The cap can thus be adjusted longitudinally of the spindle while 100 it is compelled to participate in the rotation of the same.

In order to regulate the weight of the cap and thus the friction of the latter on the yarn, a suitable number of rings 10 may 105 be arranged loosely about the neck 2 and supported on the shoulder 1.

An elastic connection between cap and spindle may be provided for, as shown in Fig. 8 where the cap is fitted with a rubber ring 22 of medium hardness and connected 110 by means of the latter to a block 23 having

- a flattened aperture 24 whereby the cap is guided on the spindle 7. The block has flanges to take the screws 29 whereby the elements are connected together. A small space 25 is left between the top flange of the cap and the head of the screw 29 so as to allow a certain amount of free play. There is also an air space 26 left between the rubber ring 22 and the block 23.
- 5 The balls 13 may also be elastically supported by means of springs 27 as shown in Figs. 10 to 14. Fig. 10 shows a ball supported vertically in this manner. In Fig. 11 the ball is supported by an obliquely arranged spring and bears against an oblique surface on the rim 11 so as to support the cap 3 against horizontal as well as vertical vibrations. The same object is attained by the arrangement shown in Fig. 12 where 10 one ball supports the cap vertically and another horizontally. Fig. 13 also shows two balls one of which supports the cap vertically and the other obliquely. Fig. 14 shows the relative position of the balls in the different rows. The springs 27 may be replaced by other cushioning elements such as felt, leather, rubber or the like. The cushions may be applied to the cage instead of to the balls.
- 15 20 All sorts of yarn from the coarsest to the finest can be spun by means of this arrangement with loose or hard twist, without injury to the fibres. High spindle speed is possible, and the yarn can be laid on the spindle or on a cap tube in any suitable manner.
- I claim:
1. In a spinning apparatus of the character described, the combination with a spindle and with a cap connected slidably to said spindle, of a plurality of rotatable supporting elements for said cap, and a stationary cage holding and controlling said supporting elements so that the yarn is subjected, during each revolution of the spindle, to a succession of instantaneous retardations.
  2. In a spinning apparatus of the character described, the combination with a spindle and with a cap connected slidably to said spindle, of a rim connected detachably to said cap, a plurality of rotatable elements bearing against said rim for supporting the cap, and a stationary cage holding and controlling said supporting elements so that the yarn is subjected, during each revolution of the spindle, to a succession of instantaneous retardations.
  3. In a spinning apparatus of the character described, the combination with a spindle and with a cap connected slidably to said spindle, of a rim connected detachably to said cap, a stationary ball cage arranged under the cap, and balls held rotatably in said cage so as to bear against said rim for supporting the cap.

4. In a spinning apparatus of the character described, the combination with a spindle and with a cap connected slidably to said spindle, of a rim connected exchangeably to the lower edge of said cap, a ball cage arranged under the cap, and balls held rotatably in said cage so as to bear against the rim for supporting the cap, said cage being formed with passages through which dust can be discharged from between the balls.

70

75

5. In a spinning apparatus of the character described, the combination with a spindle and with a cap connected slidably to said spindle, of a rim connected exchangeably to the lower edge of said cap, an annular ball cage arranged under said cap, and balls held rotatably in said cage so as to bear against the rim for supporting the cap.

80

6. In a spinning apparatus of the character described, the combination with a spindle, a ring rail and a cap connected slidably to said spindle, of a rim connected detachably to the lower edge of said cap, a split ring connected to the ring rail under the cap, an annular ball cage arranged in said ring, a screw fitted in the ring rail so as to clamp the ring to the rail and to the cage, and balls held rotatably in said cage so as to bear against said rim for supporting the cap.

85

90

7. In a spinning apparatus of the character described the combination with a spindle and with a cap connected slidably to said spindle, of a rim connected detachably to the lower edge of the cap, an annular cage composed of detachable parts arranged under the cap, and balls held rotatably between the parts of the cage so as to bear against said rim for supporting the cap.

95

8. In a spinning apparatus of the character described, the combination with a spindle and with a cap connected slidably to said spindle, of a rim connected detachably to the lower edge of the cap, an annular cage composed of detachable parts arranged under the cap, and rotatable elements held resiliently in said cage so as to bear against the rim for supporting the cap.

100

105

9. In a spinning apparatus of the character described, the combination with a spindle and with a cap connected slidably to said spindle, of a rim connected detachably to the lower edge of the cap, an annular cage composed of detachable parts arranged under the cap, and balls held rotatably and resiliently in said cage so as to bear against said rim and support the cap vertically and horizontally.

115

120

10. In a spinning apparatus of the character described, the combination with a spindle and with a cap connected slidably to said spindle, of a rim connected detachably to the lower edge of the cap and formed with an inclined bearing surface, a cage arranged under the cap, balls held rotatably in said cage so as to bear against the inclined sur-

125

130

face of the rim for supporting the cap, and springs arranged perpendicularly to said inclined surface as supports for the balls.

11. In a spinning apparatus of the character described, the combination with a spindle, and with a cap for said spindle, of a flanged block arranged slidably on the spindle as a guide for the cap, bolts connecting the cap loosely to the flange of said block, an elastic ring interposed between the cap and the flanges, a stationary cage arranged

under the cap, and balls held rotatably in said cage as supports for the cap.

12. In a spinning apparatus of the character described, the combination with a spindle and with a cap connected slidably to said spindle, of a cage arranged under the cap, balls held rotatably in said cage as supports for the cap, and weights arranged loosely on the cap for regulating the friction of the latter on the yarn.

WILLY FREUND.
